UNITED STATES PATENT OFFICE.

ARTHUR P. TAMM, OF MILWAUKEE, WISCONSIN, ASSIGNOR TO UNIVERSAL CONCRETE PRODUCTS COMPANY, OF CHICAGO, ILLINOIS, A CORPORATION OF DELAWARE.

CONCRETE-POLE-FORMING PROCESS.

1,262,863.

Specification of Letters Patent. Patented Apr. 16, 1918.

Application filed December 26, 1917. Serial No. 208,954.

To all whom it may concern:

Be it known that I, ARTHUR P. TAMM, a citizen of the United States, and a resident of Milwaukee, in the county of Milwaukee and State of Wisconsin, have invented certain new and useful Improvements in Concrete-Pole-Forming Processes, of which the following is a specification.

My invention relates to an improved concrete forming process particularly adaptable in the manufacture of tubular poles, posts, pipes or other tubular products by centrifugal force.

In the manufacture of concrete tubular products by the centrifugal process, a reinforcing structure is first placed in the mold and then concrete poured in in sufficient quantity to give the desired wall thickness when the mold is rotated and centrifugal force becomes effective. It has been found that if the concrete at any part of the mold extends entirely across the mold, that is, closes the mold diametrically, the concrete will not separate at that point and distribute itself to form a structure of uniform wall surface when the mold is rotated.

Where the mold used comprises two semi-circular halves and can be laid down during filling of one of the halves, such concentration and diametral filling of the mold cannot happen. However, where the tubular mold is set on end or inclined during charging in of concrete, and the mold then brought into horizontal position preparatory to being inserted into a machine for axial rotation, the concrete at that end of the pole which was lowermost during filling will not always flow down and will diametrically entirely fill the mold at that point, and then when the mold is rotated the concrete will not be uniformly distributed and unequal wall thickness results. I have found that if, after filling of the mold and after return thereof to horizontal position, a passageway is forced through the concrete where it solidly fills the mold, the concrete will then respond to centrifugal force and will distribute itself uniformly to form a wall of the desired uniform thickness. Such passageway or opening can readily be made in the concrete by the insertion of a bar or other suitable implement through the pole end and the solid concrete. I am not certain just why the provision of such passageway or opening through the concrete results in uniform dis-

tribution. It may be that the suction at the end of the pole due to the compacting of the concrete at that end during filling prevents the concrete from assuming a common level during application of centrifugal force and 60 that the forcing of a passageway through the solid sections of the concrete permits the entrance of air into and through the hole to break the suction effect, or it may be that a starting or priming opening is necessary before centrifugal action can become effective 65 to distribute the concrete. It is not necessary that the passageway through the concrete extend axially through the concrete as I have found that a passageway in any direction through the concrete to break the solidity suffices to cause uniform distribution of the concrete under centrifugal action.

On the accompanying drawing

Figure 1 is a vertical diametral section of 75 a mold with the concrete therein and showing the application of a bar for forcing a passageway through the solid sections of the concrete, and

Fig. 2 shows a plug for closing the mold 80 end during filling.

The mold 1 shown is cylindrical and slightly tapering and has the closure plate 2 at one end provided with the threaded opening 3 for receiving a plug 4. A suitable reinforcing structure 5 is inserted in the mold and alined by suitable spacers 6. The plug 4 is then applied and the mold raised into vertical position with its closed end down or inclined sufficiently so that concrete can 90 be poured therein in quantities sufficient to form the desired wall thickness when the mold is subjected to axial rotation and centrifugal force. After charging in of the concrete material the mold is restored to 95 horizontal position preparatory to being inserted in a machine for rotating it, but before rotation is started the plug 4 is removed and a suitable implement, such as the bar 7, is inserted through the opening 100 3 and through those sections of the concrete where the concrete solidly diametrically fills the mold. After filling the mold and returning it to horizontal position I find that the concrete at the closed end usually refuses to flow down and entirely closes the mold diametrically. It may be that at other parts of the mold the concrete likewise refuses to flow. However, by inserting the bar 7 a passageway is made through these 110

sections and then when the mold is rotated centrifugal action will become effective and on account of these passageways the concrete will respond and will uniformly distribute itself and form walls of uniform thickness. It is not necessary that the passageway through the solid concrete sections extend axially with reference to the mold as I have found that no matter what the direction is, so long as the passageway extends entirely through and a continuous air passageway is formed longitudinally through the mold, the concrete will readily respond at all points of the mold to centrifugal force.

15 Having described my improved process, I claim:

1. The process of manufacturing tubular concrete products which consists in inclining a tubular mold with its lower end closed, 20 charging in concrete material in quantity sufficient for the desired wall thickness, then restoring the mold to horizontal position, then opening the end and forcing a passageway through the concrete at those sections 25 of the mold where it extends entirely diametrically across and closes the mold, and then subjecting the mold to axial rotation and the concrete to centrifugal force.

2. The process of manufacturing tubular concrete products, which consists in inclining a tubular mold with its lower end closed, 30 charging in concrete in quantity sufficient to produce the desired wall thickness when the concrete is subjected to centrifugal force, then inserting an implement through the mold end to force a passageway through the concrete and those sections of the mold where the concrete extends entirely across and diametrically fills the mold to thereby 35 provide a passageway through such sections, 40 and then axially rotating the mold to subject the concrete to centrifugal action.

3. The process of filling and preparing a concrete mold preparatory to subjecting it to axial rotation for the generation of 45 centrifugal force which consists in pouring in the concrete and then inserting a suitable implement longitudinally into the mold to insure air passageway therethrough from one end to the other before the mold is subjected to rotation.

In witness whereof, I hereunto subscribe my name this 20th day of December, A. D. 1917.

ARTHUR P. TAMM.
